UNITED STATES PATENT OFFICE.

SYLVESTER L. GOOKIN, OF BOSTON, MASSACHUSETTS, ASSIGNOR TO UNITED SHOE MACHINERY CORPORATION, OF PATERSON, NEW JERSEY, A CORPORATION OF NEW JERSEY.

MACHINE FOR SETTING FASTENERS.

Original application filed June 15, 1918, Serial No. 240,202. Patent No. 1,371,364, dated March 15, 1921.
Divided and this application filed June 30, 1920. Serial No. 392,910.

To all whom it may concern:

Be it known that I, SYLVESTER L. GOOKIN, a citizen of the United States, residing at Boston, in the county of Suffolk and State 5 of Massachusetts, have invented certain Improvements in Machines for Setting Fasteners, of which the following description, in connection with the accompanying drawings, is a specification, like reference characters on the drawings indicating like parts in the several figures.

This invention relates to machines for inserting fasteners and more especially to those for setting compound fasteners. In 15 United States Letters Patent 1,371,364 granted March 15, 1921 upon my application, I have shown a machine for setting two-part fasteners, said patent disclosing a hopper in which both parts of the fasteners 20 may be intermingled and from which they are segregated and fed so that exclusively those of one shape or size will be fed to one side of the setting locality while exclusively those of another shape or size will be fed 25 to the other side of the locality and there assembled in cooperative relation and clenched. So far as the former patent is concerned this present application is a division.

30 Although the type of fastener illustrated in my former patent and also in this present application is said to comprise "telescopic eyelets" the primary object of this phase of the invention is to segregate and 35 feed the complementary parts of compound fasteners differing from each other in any physical respect that will permit such control. Heretofore machines for feeding and setting compound fasteners have been provided with separate hoppers for the different kinds of fastener parts, and while the provision of a plurality of hoppers has encumbered the machines and has increased the problems of organization and the cost 40 of manufacture, it has been considered necessary in every case when compound fasteners are used. This invention, therefore, overcomes the aforesaid difficulties of organization and reduces the cost of manufacture 45 by providing a single hopper in which assorted fastener parts may be initially intermingled in a mass, and by which they will be automatically segregated and fed according to kind.

A feature of the invention consists in 55 means constructed and arranged to segregate and feed dissimilar fastener parts from a mass so that only those of one kind will pass from the hopper into each raceway, the raceways being formed and arranged to conduct the segregated fastener parts along different courses to the setting mechanism by which they are assembled and clenched in cooperative relation. According to a simple 60 and convenient embodiment of the invention such segregation may be effected by providing the hopper with outlet ports of different proportions corresponding to those of the fastener parts, each outlet port being of such shape and size as to permit the 65 escape of fastener parts of one kind and to prevent the escape of all other fastener parts.

A construction embodying the aforesaid features is illustrated by the accompanying 70 drawings and is hereinafter described and claimed.

In the drawings,

Fig. 1 is a perspective view including a single hopper and two raceways constructed 75 and organized in accordance with this invention, together with fragments of suitable setting mechanism to which the fastener parts are supplied;

Fig. 2 is a section in a vertical plane 80 through the elements at the setting locality, showing two cooperative setting tools in the act of taking the two complementary parts of a two-part fastener from their respective raceways;

Fig. 3 is a sectional view including a fragment of the hopper in which outlet ports for one kind of fastener part are provided; and

Fig. 4 is a view similar to Fig. 3 showing another fragment of the hopper in which outlet ports for the other kind of fastener are provided.

In describing the invention with regard to two-part fasteners, both kinds of fastener parts are intermingled in massed formation in a hopper 10 which, in the illustrated machine, has an annular wall 11 and is arranged so that its axis is inclined. Two raceways indicated at 12 and 13 are rigidly 100 connected to the hopper so that they, together with the hopper, may be oscillated 105 to shift their delivery ends to and from

registration with cooperative setting tools 14 and 15. According to the construction shown the raceways are arranged to receive fastener parts from opposite sides of the 5 hopper, the annular wall 11 being provided with outlet ports 16 at one side and with outlet ports 17 at the opposite side.

The complemental fastener parts shown by the drawings are eyelets of telescopic proportions, those of smaller diameter being indicated at 18 and those of larger diameter being indicated at 19. It is to be understood, however, that the invention is not limited to any particular type of compound fastener. 10 The assorted fastener parts massed in the hopper are supported by the bottom wall 20 of the latter and may be moved about in the hopper by any suitable or preferred means such as a rotary or oscillatory brush, a portion 15 of which is indicated at 21 in Fig. 1.

The invention utilizes physically different characteristics of the fastener parts to control segregation, and since eyelets of telescopic proportions are represented for the 20 purpose of disclosing the principles of the invention the particular physical characteristics of such eyelets will be described. The eyelets 18, for example, have relatively small diameter and their barrel portions are relatively long, whereas the eyelets 19 have relatively large diameter and their barrel portions are relatively short. Accordingly the outlet ports 16 for the eyelets 18 are relatively narrow and deep, while the ports 17 25 for the eyelets 19 are relatively wide and less deep. The proportions are such that the eyelets 18, when standing on their flanged ends as shown by Fig. 4, may pass freely through the ports 16 and thus enter the upper end of the raceway 12. On the other hand, the eyelets 19 can not escape through the ports 16 because the width of the latter is less than the diameter of the barrel portions. These conditions are clearly shown 30 by Fig. 3. Again, the eyelets 19 standing on their flanged ends may pass freely through the ports 17 and thus enter the raceway 13 but the eyelets 18 can not escape through these ports because their barrel portions are too long. These conditions are clearly shown by Fig. 4. It sometimes happens that two complemental fastener parts 35 will become nested as represented at the right of Fig. 4, and when this occurs they are prevented from escaping from the hopper because the ports 16 are too narrow for the outer eyelet while the ports 17 are too shallow for the inner eyelet. Nested eyelets are therefore retained in the hopper until 40 they become separated by the brush 21 or by tumbling. Any desired number of outlet ports may be provided, and if the construction includes more than one of each size they may be grouped closely in serial relation so that if the lower edge of the annular 45

wall 11 is cut away as indicated at 22 to provide a continuous space for the flanges resting on the bottom wall 20 it will not be excessively weakened. It is obvious that the eyelets can not escape in any case unless their flanged ends are resting on the bottom wall.

Although the work-punching devices and the setting tools herein illustrated are the same as those shown in the aforesaid patent 75 they may be described briefly. A tubular punching tool is indicated at 23 and a solid punch-block for cooperating therewith is indicated at 24. As shown by Figs. 1 and 2 these punching devices are separated to 80 clear an article of work comprising layers 25 and 26. The work rests on a support 27 and its upper edge is in contact with an edge-gage 28. The punching tools are brought together at one side of the support 85 27 to punch a hole 30 in the work without displacing the latter from the support 27. When the punching operation has been executed the tools 23 and 24 are both retracted from the work and are then moved laterally to the positions shown by Fig. 2, the setting tools 14 and 15 being thereby moved into registration with the punched hole.

The setting tools are then moved toward each other, and during the first stages of such movement they enter the leading eyelets at the delivery ends of the raceways respectively as shown by Fig. 2. At this stage of the cycle of operations the delivery ends of the raceways move laterally so as to 90 clear the setting tools, and the latter continue to move toward each other, first to assemble the eyelets in telescopic relation in the work and then to clench one or both eyelets.

No attempt has been made to represent herein the mechanism by which the setting tools are moved laterally to feed the work, and it will be sufficient for present purposes to state that the heads 31 and 32 in which the 95 punching tools and setting tools are mounted are reciprocated in such manner as to impart feeding motion to the work while the setting tools are in clenching position.

Referring to Fig. 1 it will be observed that the raceway 12 is so formed as to invert the eyelets that pass through it but that the raceway 13 does not embody such feature. Consequently, although both kinds of eyelets stand on their flanged ends when passing through the outlet ports of the hopper, they are delivered to the setting tools in such relation that their flanges will lie against opposite sides of the work. A bracket 33 connects and braces the raceways and the hopper rigidly so that they form a detachable unit, and the bracket is clamped by wing-nuts, as shown at 34, to an oscillatory holder by which the delivery ends of the raceways are reciprocated laterally to 120 125 130

present the eyelets to the setting tools and then to clear the latter as hereinbefore stated.

Having thus described my invention, what I claim as new and desire to secure by Letters Patent of the United States is:

1. In a fastener-setting machine, a hopper, and a plurality of fastener raceways coupled thereto and constructed and arranged to carry fasteners of different characters, said hopper being constructed and arranged to deliver fasteners of different characters to the raceways respectively in a predetermined relation and to prevent the delivery 15 to a raceway of more than one style of fastener.

2. In a fastener-setting machine, a hopper for containing assorted fasteners, a plurality of raceways contiguous to said hopper for 20 conducting the fasteners therefrom, said hopper having one or more emission ports contiguous to each of said raceways for sorting the fasteners, the port or ports cooperative with one raceway being unlike the other 25 port or ports, the raceways controlling the position of the fasteners delivered through said ports, each being formed to permit the passage of one kind of fastener and to prevent the passage of another kind of fastener.

3. In a fastener-setting machine, a hopper, and a pair of raceways coupled thereto, the upstanding wall of said hopper being provided with ports communicating with one raceway which are relatively deep and narrow and with ports communicating with the other raceway which are relatively shallow and broad.

4. In a fastener-setting machine, two raceways constructed and arranged to carry 40 different styles of fasteners, a single hopper arranged to supply both raceways, said types of fasteners being adapted to become nested within one another, said hopper being constructed and arranged to supply fasteners 45 of only one style to one of the raceways, and an agitator constructed and arranged to stir up the mass of fasteners and thereby to disengage those fasteners which have become nested.

5. The combination with a hopper having 50 outlet ports of various shapes for segregating and positioning dissimilarly shaped fas-

teners according to their shapes, and raceways arranged to conduct the fasteners from said ports so as to maintain the segregated 55 relation and position of the fasteners.

6. A machine comprising tools formed and arranged to set eyelets in telescopic relation, a hopper having dissimilarly proportioned outlet ports for segregating the 60 complementary parts of telescopically proportioned eyelets from a mass of assorted eyelets, and raceways constructed and arranged to conduct the segregated eyelets in segregated relation from said ports and deliver them in potential telescopic relation to said tools.

7. The combination with a hopper for containing assorted fastener parts, of a plurality of raceways each adjoining said hopper, said elements being constructed and arranged to segregate the fastener parts and cause those of one kind to enter one raceway and those of another kind to enter another raceway, also to prevent more than one kind 75 from entering any one raceway.

8. A hopper having dissimilar outlet ports in its upstanding wall arranged to emit dissimilar fastener parts respectively from a 80 mass of assorted parts.

9. The combination with a hopper for containing assorted eyelets of telescopic proportions, of two raceways adjoining said hopper, the latter having an emission port in cooperative relation to one of said raceways and another emission port in cooperative relation to the other one of the raceways, one of said ports being formed to receive eyelets of relatively large diameter and to prevent the passage of eyelets of relatively 90 long length, and the other one of said ports being formed to receive eyelets of relatively long length and to prevent the passage of eyelets of relatively large diameter.

10. A hopper one wall of which has one 95 or more outlet ports of one shape and one or more outlet ports of another shape greater in one dimension and smaller in another dimension than corresponding dimensions of the first said ports.

In testimony whereof I have signed my name to this specification.

SYLVESTER L. GOOKIN.
